UNITED STATES PATENT OFFICE.

HENRY S. HALE, OF PHILADELPHIA, PENNSYLVANIA.

FOLDING BED.

SPECIFICATION forming part of Letters Patent No. 431,657, dated July 8, 1890.

Application filed May 8, 1889. Serial No. 310,015. (No model.)

To all whom it may concern:

Be it known that I, HENRY S. HALE, of Philadelphia, in the county of Philadelphia and State of Pennsylvania, have invented an improvement in Folding Beds, of which the following is a specification.

My invention relates to folding beds; and it consists of certain improvements which are fully set forth in the following specification and shown in the accompanying drawings, which form a part thereof. A serious fault that exists in many folding beds is that they are without means to lock the feet at the foot of the bed in position when the bed is lowered, so that the said feet cannot be pushed or knocked out of place by accident. In folding beds having mechanically-operated foot-boards, or those in which the foot-board is connected by mechanical devices with some stationary part of the structure, and thereby caused to swing out in lowering the bed, the foot-board and legs are practically locked against displacement. In folding beds having the feet at the foot of the bed operated by gravity this is not the case, and hence the liability of their displacement, and the present invention is intended to accomplish the locking of the said feet automatically, so that the moment the bed is lowered and the feet come in contact with the floor they are firmly locked to the body of the bed and cannot be shifted or released until the bed is raised, when they are again automatically unlocked.

In the drawings, Figure 1 is a sectional side elevation of a folding bed embodying my invention. Fig. 2 is a longitudinal sectional view of same on the line X X of Fig. 3. Fig. 3 is a plan view of the end or foot of a folding bed illustrating my invention, showing the bed opened. Fig. 4 is a vertical sectional view through the line Y Y of Fig. 6. Fig. 5 is a sectional side elevation of the foot or end of the bed, illustrating the operation of my invention when the bed is being raised or folded up or vice versa; and Fig. 6 is a front elevation of a portion of the closed bed.

A is the main body of the bed, having the side boards B and foot-board C. D is the stationary upright portion or head of the bed.

It is immaterial to the present invention in

what manner the bed is made to fold and unfold. I prefer, however, the construction shown in Fig. 1, in which the side boards B are pivoted at b to the segments E, working in the racks F, and the heads of these side boards are provided with hooks or arms G, supporting a sliding box or receptacle containing counterbalancing-weight H. This construction, however, is no part of the present invention, and may, if desired, be replaced by any other mechanism suited to the purpose.

I are the feet, hinged at i to the main body of the bed or to the foot-board C.

J are supports secured to the feet I, to which are pivoted the locking-levers K. The two arms of the levers K are arranged at an angle to each other, and one arm k is weighted, so as to normally raise the other or locking-arm, which is provided with a slightly-curved or flattened end.

The main body of the bed is provided at its foot or end with an opening L, through which the raised or locking arms of the levers K may project.

M are angular plates secured upon that edge of the opening L most distant from the foot-board C and adapted to receive the flattened or curved ends k' of the levers K. The ends of the weighted arms k of the levers K extend into recesses N within the feet I.

O are pins carried by supports J within the feet I, and having their ends projecting into the recesses N. Springs P are employed to actuate the pins O and encircle them for convenience of construction. The ends of the weighted arms k of the levers K extending into the recess N rest upon the ends of the pins O therein, and it is apparent that as these pins are projected or withdrawn a greater or less distance within the recesses N the arms k of the levers will be correspondingly raised and lowered. The springs acting on the pins O may be arranged to either force the pins in when relieved or force them out. In Fig. 2 the springs P are shown as adapted to lift the pins O just as soon as the weighted parts k of the levers K are lifted from the said pins and made to assume the position shown in Fig. 4 by striking against the foot-board C of the bed when the bed is folded up. When the bed is being lowered, the levers K are freed, and the weighted ends k press upon the up-

per parts of the pins O and force the heads o of the pins down, so as to come into contact with the floor. As soon as the heads o strike the floor the pins are projected upward within the feet and oscillate the levers K, causing the ends k' to be forced down into the crotch of the angle-iron M on the bed-bottom B. This holds the legs from being shifted. The pressure comes directly on the heads of the pins, and hence the end k' of the lever is held tightly down into the crotch of the angle-plate, and thus prevents the shifting of the feet I. In this construction the spring P is made sufficiently light to be overcome by the weight of the weighted end k. In Figs. 4 and 5 the springs are shown as adapted to force down the pins O, so as to project their heads below the feet when the latter are raised. In this case the springs are compressed when the heads o strike the floor. The levers K are constructed the same in this case as in the other, but they are not relied upon to project the pins O. Either construction may be employed, as desired.

25 The hinged feet I, as shown in Fig. 6, may form part of a decoration or ornamentation of the front of the closed bed. When the springs P act to pull in the pins O, they are of such strength that the weight k of the arm K is sufficiently heavy to push the pins O out and compress the spring. When, however, the bed is being folded up, the lever k' strikes the foot-board C, Fig. 4, and this removes the weight k from the spring, which then instantaneously pulls in the pin. The spring P is not a necessity, and, if used, should be made light. These pins act as pressure devices for actuating the locking-levers K. It is evident that the principle of locking the feet by the weight 40 of the bed applied through positive locking mechanism may be applied in numerous ways; hence the present drawings are only designed to illustrate the principle of the invention.

Having now described the parts of my apparatus, their operation will be understood from the following description: When the bed is opened, as shown in Figs. 1, 2, and 3, and the feet I rest upon the floor, the projecting heads O of the pins are forced up, projecting the upper parts thereof a greater distance into the recess N and correspondingly raising the weighted ends k of the levers K. This forces down the other ends of the levers, bringing their flattened or curved ends k' in contact with the crotch of the angular plates M. Now it is apparent that the feet I will be rigidly locked against lateral movement, since the levers K, which are pivoted to the feet, are locked into the angular plates M by the pins O, the horizontal portions of these plates preventing the locking ends of the levers from descending, which would allow of outward movement to the feet, and since the pressure of the pins O upon the ends k prevents them from rising the vertical parts of the plates M prevent inward movement to the feet. When the bed is

lifted so that the feet I are raised from the floor, the springs P depress the bolts, allowing the weighted ends k of the levers K to descend, thus freeing the locking ends of the levers from the plates M and allowing them to rise up through the openings N, as shown in Fig. 5. The legs will now fold against the main body of the bed A as it is raised, as shown in Figs. 4 and 6, the foot-board C occupying a horizontal position. For a neat appearance the main body A may be provided with ornamental projecting parts, against the ends of which the feet will fit when the latter are folded, so as to conceal from view the projecting ends of the bolts and give to the closed bed the appearance of a wardrobe or closet, as shown in Figs. 4 and 6. It is apparent that only one of the lever-locking devices may be employed, though it will afford less security than the two levers, as shown.

While I prefer the details of construction which are here shown, it is apparent that they may be modified in many ways without departing from the principles of my invention, and are not to be taken as limitations of it.

What I claim as new, and desire to secure by Letters Patent, is—

1. A folding bed having feet loosely pivoted at the foot thereof and operated by gravity, in combination with mechanism controlled by the feet to automatically lock said feet against lateral movement when the bed is opened or unfolded, consisting of a lever carried by the feet, a catch for the lever on the bed-body, and a movable extension for operating the lever, projecting below the feet, so as to strike the floor.

2. A folding bed having feet pivoted at the foot thereof, in combination with an automatic lock carried by said feet to lock them against lateral movement when the bed is opened or unfolded, consisting of a lever movable with the feet, a catch for the lever on the bed-body, and a spring-actuated part adapted to strike the floor when the bed is lowered to hold the lever in the catch.

3. A folding bed having feet pivoted at its foot, and in combination with a lever carried by the foot and adapted to lock the feet to the main or body portion of the bed, and pressure devices also carried by the feet and extending from the lever to a point below the feet, so as to strike floor, so as to employ the weight of the bed to lock the lever in locking position when the bed is down.

4. In a folding bed, the combination of the pivoted body part with feet hinged to the body part at its foot portion, and a movable locking-connection between the feet and body part of the bed, and a bolt extending down below the feet, so as to strike the floor and be shifted upon lowering the bed to operate said locking-connection and lock said feet to the body part.

5. In a folding bed, the combination of the

- main body of the bed, feet pivoted thereto, a weighted locking-lever carried thereby, and a bolt secured to said feet, having its upper end arranged to strike the lever to lock it to the bed and its lower end projecting beyond the bottom of the said feet to strike the floor, the whole operating to lock the feet against lateral movement when the bed is lowered or unfolded.
- 5 6. In a folding bed, the combination of the main body of the bed, provided with an opening near its foot, catches in said opening, feet pivoted to the foot of said bed, locking-levers carried by said feet, operated to engage said catches, and movable pressure devices carried by said feet and projecting below them to strike the floor and be thereby actuated to lock said levers in said catches when the bed is opened and the feet rest upon the floor.
- 10 7. In a folding bed, the combination of the main body of the bed, feet pivoted thereto, a weighted locking-lever carried thereby, and a spring-actuated bolt secured to said feet, having its upper end arranged to strike the lever to lock it to the bed and its lower end projecting beyond the bottom of the said feet
- 15 to strike the floor, the whole operating to lock the feet against lateral movement when the bed is lowered or unfolded.
- 20 8. The combination, in a folding bed, of the pivoted body part, the hinged feet at the foot thereof, operating by gravity, and a lock carried by but movable with and also independent of the feet, but projecting below them to strike the floor and actuated by the weight of the bed to lock said feet to the body part.
- 25 9. In a folding bed, the combination of the main body of the bed, provided with an opening near its foot, a catch in said opening, feet pivoted to the foot of said bed, a locking-lever carried by said feet, adapted to engage with said catch and extending through said opening, and a spring-bolt carried by said feet, with its upper part arranged to operate the lever and its lower end projecting beyond the bottom of the feet.

In testimony of which invention I hereunto set my hand.
